Fig. 9.

Fig. 10.

Fig. 11.

Fig. 12.

Fig. 13.

Fig. 14.

FIG. 1 is a front elevational view of a pair of motorcycle fairing attachments showing my new design; FIG. 2 is a rear elevational view thereof;

FIG. 3 is a left side elevational view of the left fairing attachment;

FIG. 4 is a right side elevational view of the right fairing attachment;

FIGS. 5 and 6 are bottom plan views of the right and left fairing attachments, respectively, to an enlarged scale;

FIG. 7 is a rear elevational view of the left fairing attachment on an enlarged scale;

FIG. 8 is a front elevational view of the left fairing attachment on an enlarged scale;

FIGS. 9 and 10 are top plan views of the right fairing attachment to an enlarged scale;

FIG. 11 is a front elevational view of the right fairing attachment to an enlarged scale;

FIG. 12 is a rear elevational view of the right fairing attachment to an enlarged scale;

FIG. 13 is a left side elevational view of the right fairing attachment to an enlarged scale; and

FIG. 14 is a right side elevational view of the left fairing attachment to an enlarged scale.

The fragmentary broken line representation of the upper part of a motorcycle fairing in FIGS. 1-4 and of a motorcycle in FIGS. 3 and 4 is for illustrative purposes only and forms no part of the invention.

I claim:

The ornamental design for a pair of motorcycle fairing attachments, as shown and described.
